UNITED STATES PATENT OFFICE.

JOHN W. MAILLOT, OF NORTH ATTLEBOROUGH, MASSACHUSETTS, ASSIGNOR
TO F. M. WHITING & CO., OF SAME PLACE.

DESIGN FOR A HANDLE FOR SPOONS, &c.

SPECIFICATION forming part of Design No. 23,057, dated February 13, 1894.

Application filed January 15, 1894. Serial No. 496,987. Term of patent 3½ years.

To all whom it may concern:

Be it known that I, JOHN W. MAILLOT, a citizen of the United States, residing at North Attleborough, Bristol county, State of Massachusetts, have invented and produced a new and original Design for Handles of Spoons and the Like, of which the following is a specification.

In the drawings: Figure 1, represents a front or face view of a spoon the handle of which is ornamented with the design. Fig. 2, shows a rear view of the spoon with the design upon that face of the handle.

Upon the faces of the spoon handle and following the outline thereof the design is arranged and composed as follows: At the head of the handle A upon its front face is located a compound scroll 1; below this on the left hand side is a compound ogee scroll 2; below this is a compound scroll 3; at the center of the handle is located a compound branch scroll 4; following the shank are flowers and

leaves 5; scroll 6, flowers and leaves 7 with a leaf like outline around the entire handle. On right hand side are located in succession 25 three compound scrolls 8.

On the rear face at the top of the handle is a compound scroll 9; below this on the left hand side are three compound scrolls 10, followed by a compound ogee scroll in center of 30 handle 11 and followed by an open scroll reaching to the bowl 12; on the right hand side are two compound ogee scrolls 13 with leaf like outline around the entire handle.

I claim—

The design for the handles of spoons, and the like as shown and described.

In testimony whereof I affix my signature in presence of two witnesses.

JOHN W. MAILLOT.

Witnesses:
